VENTILATING WINDOW MECHANISM

John H. Roethel, Detroit, Mich., assignor to Automobile Ventilation, Inc., Detroit, Mich., a corporation of Michigan

Application April 6, 1936, Serial No. 73,050

17 Claims. (Cl. 296—44)

This invention relates to ventilating windows for vehicle bodies and more particularly to window ventilation in doors of automobile bodies. An object of the invention is to provide an improved, relatively simple and economical mechanism for raising and lowering the window glass in the body or door and for providing a ventilating slot at the forward edge of the glass when the glass is fully raised, and also for sliding the glass horizontally in its plane into and out of position to close said ventilating slot. The present application is a continuation in part of my co-pending application Serial No. 735,768 filed July 18, 1934.

15 In accordance with the present embodiment of the invention it is desirable to raise the glass vertically into ventilating position in the window opening and thence shift it forwardly or horizontally into fully closed position. Such a construction has the important advantage of insuring the tight closing of the window when the regulator has been operated to the limit of its travel in one direction, thus preventing the danger of accidentally leaving the window partly 20 open at its top, as a consequence of the regulator mechanism over-running in the use of structures in which the glass is first elevated into fully closed position and then shifted rearwardly to ventilating position.

25 30 Where it is desirable to use the present structure, in which the window is first shifted vertically into ventilating position, in a vehicle door hinged at its forward edge, difficulty has been experienced in causing the rear edge of the glass 35 to pass the lock mechanism during its vertical travel except where an undesirably wide rear door pillar is provided.

The foregoing disadvantages are overcome by the present invention whereby means is provided 40 for shifting or displacing the glass horizontally during its vertical travel so as to pass or clear any latch construction, thus permitting a deep channel or glass runway at the upper rear edge of the glass, without, however, necessitating any increase 45 in the width or thickness of the rear door pillar.

Another object of the invention is to provide a construction in which the operating mechanism for effecting the vertical movement of the glass, also functions to shift the glass horizontally in 50 two directions.

Another object of the invention is to provide an improved construction of the foregoing character in which the operating arm or arms of the regulator mechanism can be quickly and easily 55 connected with the window glass or the rail or

channel carried thereby; and one in which the operating cam is so constructed and arranged as to shift the glass longitudinally of the vehicle when elevated into and out of ventilating position and to positively control the initial downward movement of the glass to insure its proper positioning with relation to the guide channels or runways for the upright edges of the glass.

A further object of the invention is to provide the upright edges of the glass with parallel angularly disposed bearing portions or surfaces extending in planes corresponding to the planes of the guide channels or runways located in the window well.

A further object of the invention is to provide an improved structure of the above character having relatively few parts and one which is relatively cheap to manufacture.

Other objects and advantages of this invention will appear in the following description and appended claims, when considered in connection with the accompanying drawings forming a part of this specification, wherein like reference characters designate corresponding parts in the several views.

In the drawings:

Fig. 1 is a fragmentary side elevation illustrating a front door of an automobile body embodying the present invention.

Fig. 2 is an enlarged fragmentary view, partly in section, illustrating the position of the operating mechanism when the glass is in ventilating position.

Fig. 3 is a vertical section, on an enlarged scale, taken substantially through lines 3—3 of Fig. 1, looking in the direction of the arrows.

Fig. 4 is a detailed section taken substantially along the line 4—4 of Fig. 3, looking in the direction of the arrows.

Fig. 5 is a detail horizontal section taken substantially along the line 5—5 of Fig. 4, in the direction of the arrows.

Fig. 6 is a detail upright section taken substantially along the line 6—6 of Fig. 4, in the direction of the arrows;

Fig. 7 is an enlarged fragmentary detail taken substantially along the line 7—7 of Fig. 2, looking in the direction of the arrows.

Fig. 8 is a view similar to Fig. 1, showing a modified form of the present invention with the window glass in fully closed position; and

Fig. 9 is a fragmentary inside elevation of the structure shown in Fig. 8 with the glass in ventilating position and located in approximately the

position from which it starts its initial downward travel.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In Figs. 1 to 7 inclusive of the drawings there is illustrated, by way of example, an automobile front door having window glass mounted therein and adapted to be elevated by a regulator mechanism into position within the window opening of the door to provide a ventilating slot between the forward edge of the glass and the adjacent door pillar. The regulator mechanism is thus operative to move the window glass into its uppermost vertical position while maintaining the glass at the same time in ventilating position. This mechanism is also operative to shift the glass forwardly or horizontally in its plane to close the ventilating slot and thus fully close the window opening. In the construction shown, the door is hinged at its forward edge and is, therefore, provided with a latch mechanism mounted in the rear pillar of the door. In order to permit the window glass to be moved vertically and upwardly into ventilating position and at the same time to prevent interference with the latch mechanism, the present invention, among other features, provides means for shifting the window glass horizontally in its plane at substantially an intermediate point between its upper and lower positions, so as to clear or avoid the latch mechanism during its vertical movement and thus enable the rear edge of the window to overlie the latch mechanism when the glass is in its top ventilating position.

As best shown in Figs. 1 and 2 of the drawings, the door comprises a front pillar 10 and a rear pillar 11 connected at their upper ends by the usual header 12. The front and rear pillars together with the header define a window opening which is adapted to be closed by means of a glass panel 13. Mounted in the front pillar 10 is a felted glass channel member 14 adapted to receive the forward edge of the glass when fully closed, as shown in full lines, Fig. 1. The channel 14 extends upwardly and rearwardly at 15 within the header 12 so as to confine the upper edge of the glass panel when closed. The rear pillar 11 is constructed so as to provide a relatively deep glass channel or runway 16 to receive the rear edge of the glass when the latter is in ventilating position, as shown in dotted lines, Fig. 1. The channel 16 is of sufficient depth to confine the rear edge of the glass when it is shifted to its forward limit to close the ventilating slot.

It will be understood that in the present instance the front pillar 10 of the door is hinged to the front body pillar so that the door is latched, when closed, at its rear edge. A latch or locking mechanism for the door may comprise a transverse rotatable shaft 17 extending through the pillar as shown in Fig. 7, this shaft being turned by means of a handle 18 to retract the latch bolt 17a. It will be seen that the shaft 17 underlies the glass channel 16 and as a result it is not possible to shift the glass in a straight ver-

tical line into and out of closed position. In the present construction the deep glass runway or channel 16 terminates at the point 19 above the shaft 17 and then narrows and slopes inwardly and downwardly at an angle as shown at 19a to 5 the point 19b. Thence the runway or channel extends downward in a vertical direction within the door pillar 11, inwardly or forwardly of the shaft 17, providing a relatively shallow channel extension 20. The front pillar 10 is provided with 10 an auxiliary glass runway or felted channel 21 located below the window sill 50 and effective, in cooperation with the shallow channel 20, to guide the window glass during the lower part of its travel.

The window regulator mechanism for raising and lowering the glass and for shifting it horizontally into and out of ventilating position may be of any suitable construction. In the present instance it comprises a mounting plate 22 secured 20 by a plurality of screws 23 or other suitable means to the inside of the door well. The plate 22 carries a pair of intermeshing gears 24 and 25 which are journaled on the plate by means of pivots 26 and 27 respectively. Secured to the pivot 26 is a swinging arm 28 and secured to the pivot 27 is a swinging arm 29, these arms being swung in opposite directions upon rotation of the gears. Secured to the outer end of each of the arms 28 and 29 is a stud or button-like device 30 having 30 a shank riveted at 30a to the end of the arm. Along the lower edge of the glass there is fastened a felted channel 31. A plate or plates 31a are spot welded to one face of the channel 31 (see Fig. 3) and have depending walls forwardly 35 flanged at 32 along their lower edges to provide, with the lower edge of the channel 31, a runway or runways 33 for the studs 30. Each runway, as shown at 34 in Fig. 3, has a constricted neck forming upper and lower tapered faces engaging 40 the tapered sides of the stud 30, and the members 31 and 32 which together form the glass retaining member, have outwardly flared bearing surfaces 35, engaged by conical spring pressed washers 36. From this construction it will be 45 seen that when the arms 28 and 29 are swung relatively to each other the studs 30 will slide horizontally in the runways or camways 33 and thus raise or lower the window glass.

Secured to the inner face of the plate 31a, by 50 welding or in any other suitable manner, is a block or member 37 into which is threaded a screw or bolt 37a carrying or supporting a roller 38. In the present instance the arm 29 has on its forward side an integral cam portion or extension 39 provided with a cam slot 40. The open lower end of the slot 40 is flared outwardly at 40a and is embossed so as to receive or permit the roller 38 to enter the slot at a predetermined time during the operation of the mechanism. 60 The upper or closed end of the cam slot 40 has an offset portion or extension 40b.

The parts are assembled when the glass 13 is in its upper closed position. The stud 30 carried by arm 28 is inserted horizontally into the end 65 of the guideway formed in the plate 31a, while at the same time the stud 30 carried by arm 29 is inserted vertically into the guideway or groove formed in the other plate 31a through a cut out or notched portion 31b in the plate. The parts are then moved into their respective positions, as shown in Fig. 1, whereupon the screw or bolt 37a carrying the roller 38 is inserted through the cam slot 40 and screwed into the block 37 to maintain the parts in assembled relation. 75

As best shown in Figs. 1 and 2, the window is counterbalanced by means of clock-like springs 41, one end of each of the springs being anchored to a pivot 26 and 27, their opposite ends being secured to struck-up lugs or members 42.

The operation of the mechanism is as follows: When the window is in its fully closed position, the operating arms 28 and 29 are in substantially vertical positions as seen in Fig. 1. When it is desired to lower the window, the operating handle 43, carrying on its shaft a pinion 44 which meshes with the gear 24, is turned in a clockwise direction. This causes the arms to swing outwardly in opposite directions, and engagement of the forward edge of the offset slot 40b with roller 38 will result in sliding the window glass horizontally into the deep channel 16 to the full line position of Fig. 2, producing the forward ventilating slot. Further operation of the regulator in the same direction will cause the stud or roller 38 to travel through the cam slot 40. This slot is so formed as to progressively force the stud forwardly during its downward vertical travel, the stud thereby moving on an oblique line indicated at 60 in Fig. 2. Thus, the outward and downward swinging movement of arms 28 and 29 produces a compound movement of the window, the inclined line 60 indicating the resultant of the vertical travel induced by studs 30a and the horizontal travel induced by roller 38 travelling in cam slot 40.

When the roller 38 nears the lower end of the cam slot the window glass will have been shifted downwardly out of the deep channel 16 to its dotted line position in Fig. 2, the forward edge of the glass engaging the channel 21 and the rear edge being in line with the channel 20.

The roller 38 does not travel out of the lower end of the cam slot 40 until preferably the glass has been shifted downwardly a slight distance past the latch handle shaft 17 so that the opposite edges of the glass are firmly guided and supported within the channels or glass runways 20 and 21. From this point the roller 38 will move downwardly along the vertical line 61 in accordance with the vertical travel of the glass.

When the glass panel is shifted from its lowered position to its raised position, by the counter-clockwise rotation of the operating handle 43, the reverse action takes place. The roller 38 enters the flared end 40a of the cam slot and is gradually shifted sidewise or horizontally during its upward vertical movement along the imaginary line 60. When the roller has traveled the full length of the main cam slot 40, the glass panel has attained the upper limit of its vertical movement and is in position to provide the ventilating slot at its forward edge. Further rotation in the operating handle 43 in the same direction causes the roller to ride into the cam slot extension 40b, and by cooperation of the rear edge thereof with the roller the glass will be shifted horizontally and forwardly in its plane to close the ventilating slot.

From the foregoing it will be seen that I have provided an improved regulator mechanism in which the movement of the regulator arms effects the horizontal movement of the window into and out of ventilating position and the vertical up and down movement of the glass panel, and during such vertical movement also effects a horizontal shifting of the glass to avoid the door handle mechanism. Thus, I have provided an efficient mechanism in which the shifting of the glass panel in several directions is effected by the

regulator arms themselves, and one which is of simple construction capable of being manufactured at low cost.

Referring now particularly to Figs. 8 and 9, there is shown in these figures a somewhat modified structure embodying the present invention. The door comprises a front pillar 70 and a rear pillar 71 connected at their upper ends by the usual header 72. The front and rear pillars together with the header define a window opening 10 which is adapted to be closed by means of a glass panel 73. The front pillar 70 contains a felted glass channel member 74 adapted to receive the forward edge of the glass when fully closed, as shown in full lines, Fig. 8. The channel 74 extends upwardly and rearwardly at 75 within the header 72 so as to confine the upper edge of the glass panel when closed. The rear pillar 71 is constructed so as to provide a relatively deep channel or runway 76 having a felt lining 77 to receive the rear edge of the glass when the latter is in ventilating position, as shown in broken lines, Fig. 8. The rear channel 76 is of sufficient depth to confine the rear edge of the glass when it is shifted to its forward limit (full lines, Fig. 8) to close the ventilating slot or opening X located at the forward upright edge of the glass.

It will be understood that in the present instance the front pillar of the door 70 is hinged to the front body pillar (not shown) so that the door is latched, when closed, at its rear edge. A latch or locking mechanism for the door comprises a transverse rotatable shaft 78 extending through the pillar 71 and being adapted to be turned by means of a handle (not shown) to retract a latch bolt (not shown).

In the present embodiment, the felted channel 76 terminates at the point 79. A separate and cooperating runway or channel 80 is located within the window well and extends downwardly and forwardly from a point adjacent the lower edge 79 of channel 76 in an angular direction with relation to the channel 76 and to the rear face of the pillar 71. The channels 76 and 80 may be secured in position within the door pillar in any suitable manner, there being shown, merely by way of illustration, a bracket 81 located at the junction of the cooperating channels for supporting them. The front pillar 70 is provided with an auxiliary glass runway or felted channel 82 located within the well below the window sill 69 and effective, in cooperation with the relatively shallow channel 74, to guide the window glass during its upward and downward travel, in an angular direction, that is, at an angle to the vertical. The channel 82 extends downwardly and forwardly in a plane parallel to the plane of the rear angular runway 80. By providing the parallel angular guide channels 80 and 82, the glass 73 clears the lock shaft 78 during its up and down travel within the door well.

As seen in Fig. 8, in position A the glass panel 73 is fully closed and in position B the glass is in its ventilating position providing a slot or opening X. It will be noted that to reach position B, the glass has travelled downwardly a slight distance during its rearward movement longitudinally of the vehicle until its rear lower edge or bearing portion 73a engages the upper portion of the angular guideway or channel 80. The lower forward edge or bearing portion 73b of the glass, in position B, is about to enter the angular channel or glass runway 82. The movement of the glass from position A to position B is positively controlled by a cam forming a part of the regu- 75

lator mechanism so that the glass is guided into position B from which position its lower forward edge can enter the inclined guide channel 82 without any further aid from the cam, as explained 5 hereinafter. In position C, Fig. 9, the rectilinear bearing portions 73a and 73b of the glass panel 73 are in engagement with the channels or guide- 10 ways 80 and 82. In this position the cam is out of engagement with the glass and no longer 15 effects or controls the movement of the glass panel. Further downward movement thereof is effected by the arm or arms of the regulator mechanism. During such movement, the glass is guided in an angular path by the channels or run- 20 ways 80 and 82.

The lower rear edge 73a of the glass panel and the lower forward edge 73b thereof are correspondingly tapered and extend in parallel angular planes which correspond to the angular parallel 25 planes in which the guides 80 and 82 extend. The lower edge of the glass panel 73 is provided with a fleted metal channel or rail member 85 having, as shown, spaced depending plates 86 containing grooves or runways 87 for the reception of studs or rollers carried by the regulator arms, as de- 30 scribed below. The metal channel or rail 85 carries a depending bracket 88 located intermediate the inner ends of the plates 86. The bracket 88 is provided with a stud or roller 89.

In the present instance the regulator mechanism for operating the glass comprises a mounting plate 90 carrying intermeshing gears 91 and 92 operated by a pinion 93 which is driven by a 35 crank or handle (not shown). The gear 91 carries a regulator arm 94 having a pivotal connection at 95 with the mounting plate. The gear 92 carries a regulator arm 96 having a pivotal connection at 97 to the mounting plate 90. The arm 94 carries adjacent its outer end a stud or roller 98 and the arm 96 carries a similar stud or roller 99, these studs or rollers being adapted to travel 40 in the grooves or runways 87.

The regulator arm 96 carries a projecting mem- 45 ber or cam 100 which may be secured to the arm in any suitable manner, as by rivets 101. The member or cam comprises a body portion 102 and a depending projecting finger or nose portion 103. A cam slot 104 is located between the portions 102 and 103. The finger 103 has a 50 cam edge or surface 105 which is adapted to engage the stud or roller 89 when the arm 96 is swung upwardly toward it, or if two arms are employed, when both arms 94 and 96 swing upwardly toward one another from the positions 55 in which they are shown in Fig. 9. The outer end of the cam edge 105 engages the stud or roller 89 and rides over it, this movement causing the roller to enter the cam slot 104 and to be engaged by the cam surface 106 of the cam body portion 102. Further upward and inward move- 60 ment of the cam 100 causes the cam surface 106 to ride over the roller and shift it into the closed end of the cam slot. As the roller travels along the cam surface 106 the glass panel 73 is shifted 65 upwardly from its broken line position B of Fig. 8 and forwardly longitudinally of the vehicle into its full line position A. Thus the cam surface 106 serves to shift the roller 89 into the cam slot and the cam surface 106 on the body portion of the 70 cam serves to shift the roller further into the cam slot and at the same time move the window upwardly and then forwardly into closed or non-ventilating position. The cam and cooperating roller together provide positive means for hold- 75 ing the glass and guiding it during its move-

ment longitudinally of the frame and during a portion of its upward and downward travel, namely from the level of position A to the slightly lower level of position B, and vice versa. The initial upward and the final downward move- 5 ments of the glass are effected by the cooperation of the arm studs 98 and 99 travelling in the run- 10 ways 87, the glass being guided in an angular path by the guide channels 80 and 82 with which the parallel tapered portions or bearing surfaces 73a 10 and 73b of the glass are in engagement. In other words, after the cam 100 has moved the glass from its fully closed position A into position B, Fig. 8, further outward and downward movement of the regulator arms 94 and 96 shifts 15 the glass downwardly, this downward travel of the glass being in an angular or inclined path due to the angularity of the guide channels and the cooperation of said channels with the tapered bearing portions or surfaces of the glass panel. 20 The various parts described operate in substantially the reverse order when the glass is elevated from its lowered position within the well to its fully closed position A of Fig. 8.

From the foregoing it will be seen that I have 25 provided a structure in which the glass travels upwardly and downwardly in an angular path to clear the latch or lock mechanism for the door and in which the edges of the glass are positively guided or directed into position within inclined 30 or angularly disposed guide channels arranged in parallelism which serve to guide the glass throughout the major part of its up and down travel in an angular direction.

I claim:

1. In an automobile body having a window opening and a window glass mounted therein for successive vertical and horizontal movements in the plane of the glass, regulator mechanism connected to the glass for shifting said glass 40 vertically into elevated position while maintaining a ventilating slot at one upright edge thereof, said mechanism including a swinging arm connected to the lower edge of the glass for raising and lowering the same, said arm having 45 a cam portion at its forward side provided with a cam slot, and a device carried by the lower edge of said glass and engageable with said slot for shifting the glass horizontally during the vertical travel of the glass.

2. A regulator mechanism for a window glass mounted in a vehicle door window opening for successive vertical and horizontal movements in its plane, comprising a pair of swinging arms connected to the lower edge of the glass for 55 raising and lowering the same, one of said arms having at its forward side an integral cam provided with a cam slot, and a roller on the lower edge of said glass between said arms and engageable with said cam slot for shifting the glass horizontally in opposite directions during the vertical travel of the glass in opposite directions.

3. A regulator mechanism for a window glass mounted in a vehicle door window opening for 65 successive vertical and horizontal movements in its plane, comprising a pair of swinging arms connected to the lower edge of the glass for raising and lowering the same, one of said arms having cam means cooperating with a device 70 on the window glass for shifting the latter forwardly during the downward travel of the glass and rearwardly during the upward travel thereof.

4. A regulator mechanism for a window glass mounted in a vehicle door window opening for 75

successive vertical and horizontal movements in its plane, comprising a pair of swinging arms connected to the lower edge of the glass for raising and lowering the same, one of said arms having a slotted cam cooperating with a device on the window glass for longitudinally shifting the glass during its vertical travel.

5. In a vehicle body having a window opening and a window glass mounted therein for successive vertical and horizontal movements in the plane of the glass, a regulator including a swinging arm connected to the lower edge of the glass for raising and lowering the same, said arm having a cam provided with a slot having an offset portion and the glass having a device travelling in the cam slot and engaging said offset portion for sliding the glass in its plane into and out of position to provide a ventilating slot at one edge of the glass, said cam also shifting the glass longitudinally during the vertical travel thereof.

6. In a vehicle body having a window opening and a window glass mounted therein for successive vertical and horizontal movements in the plane of the glass, a regulator including a swinging arm connected to the lower edge of the glass for raising and lowering the same, said arm having a cam provided with a slot having an extension and the glass having a device travelling in the cam slot and engageable with said extension for sliding the glass in its plane into and out of position to provide a ventilating slot at one edge of the glass, said cam also shifting the glass longitudinally during the vertical travel thereof, and said cam being formed in an extension of the arm at the forward side of the latter when the glass is elevated.

7. In a vehicle body having a window opening and a window glass mounted therein for successive vertical and horizontal movements in the plane of the glass, a regulator including a swinging arm connected to the lower edge of the glass for raising and lowering the same, said arm having an extension provided with a curved cam slot terminating at one upper end in an offset portion, and a device on the lower edge of the glass adapted to engage in said curved slot to shift the glass longitudinally during its vertical travel and also adapted to engage in said offset portion to shift the glass longitudinally in its plane into and out of position to provide a ventilating slot at one edge of the glass.

8. In a vehicle body having a window opening and a window glass mounted therein for successive vertical and horizontal movements in the plane of the glass, front and rear oppositely swinging regulator arms connected to the glass for raising and lowering the same, a stud on the lower edge of the glass, and a cam extension on said rear arm positioned intermediate the arms when the glass is raised for longitudinally shifting the glass during its vertical travel.

9. In a vehicle body having a window opening and a window glass mounted therein for successive vertical and horizontal movements in the plane of the glass, front and rear oppositely swinging regulator arms connected to the glass for raising and lowering the same, a stud on the lower edge of the glass, and a cam extension on said rear arm positioned intermediate the arms when the glass is raised for longitudinally shifting the glass during its vertical travel, said extension also having means cooperating with the stud for shifting the glass longitudinally in its plane when in elevated position.

10. In a vehicle body having a window opening and a window glass mounted therein for successive vertical and horizontal movements in the plane of the glass, front and rear oppositely swinging regulator arms connected to the glass for raising and lowering the same, a stud on the lower edge of the glass, and a cam extension on said rear arm positioned intermediate the arms when the glass is raised for longitudinally shifting the glass in opposite directions during its vertical travel in opposite directions.

11. A regulator mechanism for a window glass mounted in a vehicle door window opening for successive vertical and horizontal movements in its plane, comprising a pair of swinging arms connected to the lower edge of the glass for raising and lowering the same, one of said arms having a slotted cam cooperating with a device on the window glass for longitudinally shifting the glass in opposite directions during its vertical travel in opposite directions, and said cam slot having an offset portion for shifting the glass in its plane when in elevated position.

12. In a vehicle body having a window opening and a window glass mounted therein for successive vertical and horizontal movements in the plane of the glass, a regulator including a swinging arm having a device at its outer end slidably in a longitudinal guideway at the lower horizontal edge of the window, a stud carried at the lower edge of the window in line with said guideway, and a cam carried by said arm and cooperable with the stud for shifting the glass longitudinally in its plane during its vertical travel.

13. In a vehicle body having a window opening and a window glass mounted therein for successive vertical and horizontal movements in the plane of the glass, a regulator including a swinging arm having a device at its outer end slidably in a longitudinal guideway at the lower horizontal edge of the window, a stud carried at the lower edge of the window in line with said guideway, and a cam carried by said arm and cooperable with the stud for shifting the glass longitudinally in its plane in a forward direction during the lowering of the glass and in a rearward direction during the raising of the glass.

14. In a regulator of the ventilating type comprising two arms, each mounted to rotate and each having a free end slidably interlocked to an edge of a window whereby rotation of the arms in opposite directions will raise or lower the window, one of the arms having, in an offset portion, a slot arranged to receive a pin secured to the window, the slot being so shaped that rotation of the arm from one terminal position will cause the slot edges to move the pin horizontally, then move the pin in a reverse horizontal direction, and then permit the pin to leave the slot, a bridge or strip at the end of the slot connecting the edges of the slot and offset so as to pass by a part in the plane of one portion of the arm and at the same time to permit the aforementioned pin secured to the window to pass out of the end of the slot.

15. In a regulator having two arms mounted to rotate and having the free ends of said arms slidably interlocked to an edge of a window so that rotation of the arms lowers or raises the window, a slot in one of the arms in a portion thereof considerably out of plane with the hub portion of the arm, these portions being separated by a bend, a third portion connecting the first two at the end of the slot and lying in a plane between the first mentioned portions so that said third

portion may pass, without striking, parts in the plane of aforesaid hub portion and so that said third portion may also pass by without striking a pin secured to the window and arranged to be received in the slot.

5 16. In a regulator adapted to raise and lower a window by the rotation of a pair of fixed center arms, an arm of said pair comprising portions in three planes, the first portion being the hub portion, lying at the center of rotation, the second portion being the outer portion and having a slot adapted to receive a pin secured to the window for the purpose of causing horizontal movement of the window, and the third portion being a strip connecting the first two portions at the end of the slot and lying in a plane between said first two portions.

10 17. In a regulator adapted to raise and lower

a window by the rotation of a pair of fixed center arms, an arm of said pair comprising portions in three planes, the first portion being the hub portion, lying at the center of rotation, the second portion being the outer portion and having a slot adapted to receive a pin secured to the window for the purpose of causing horizontal movement of the window, and the third portion being a strip connecting the first two portions at the end of the slot and lying in a plane between said first two portions, the purpose of such interplanar situation of said third portion being to permit, on one side, passage of parts in the plane of the first, or hub, portion, and, on the other side, passage of the aforementioned pin 10 secured to the window.

15 JOHN H. ROETHEL.
